Des. 206,729

Patented Jan. 17, 1967

206,729

PRESS FOR HEAT SEALING PLASTIC MATERIALS OR THE LIKE

Theodore R. Finke, Euclid, Ohio, assignor to The Euclid Products Co., Inc., Willoughby, Ohio, a corporation of Ohio

Filed July 29, 1966, Ser. No. 3,250

Term of patent 14 years

(Cl. D55—1)

Fig. 2

Fig. 1

Fig. 3

FIGURE 1 is a side elevation of a press for heat sealing plastic materials or the like, showing my new design;

FIGURE 2 is a plan thereof; and

FIGURE 3 is a perspective thereof.

The dominant features of my design reside in the portion shown in full lines.

I claim:

The ornamental design for a press for heat sealing plastic materials or the like, substantially as shown and described.
